UNITED STATES PATENT OFFICE.

ARNOLD WILD, OF DANIELSON, CONNECTICUT, ASSIGNOR TO DRAPER CORPORATION,
OF HOPEDALE, MASSACHUSETTS, A CORPORATION OF MAINE.

TENSION DEVICE FOR SHUTTLES.

1,350,630.

Specification of Letters Patent. Patented Aug. 24, 1920.

Application filed February 21, 1920. Serial No. 360,524.

To all whom it may concern:

Be it known that I, ARNOLD WILD, a citizen of the United States, and resident of Danielson, county of Windham, State of Connecticut, have invented an Improvement in Tension Devices for Shuttles, of which the following description, in connection with the accompanying drawing, is a specification, like characters on the drawing representing like parts.

This invention relates to improvements in thread guiding and tension mechanisms for loom shuttles and the object thereof is to provide a novel form of tension device which will impose a uniform tension upon the thread and which will also aid in preventing the thread from being thrown out of the shuttle eye.

A further object of the invention is to provide a tension device which will present a relatively long thread engaging surface.

A further object of the invention is to provide a thread guiding and tension device for automatic filling replenishing loom shuttles which will automatically engage the thread during the flight of the shuttle across the loom and facilitate the threading of the eye and the retention of the thread within the eye.

30 A further object of the invention is to provide a thread guiding and tension device which can readily be applied to usual forms of shuttles without modification of the shuttle or material changes in the form of the threading device.

The invention is disclosed herein as applied to a shuttle adapted for use in automatic filling replenishing looms, but it will be understood that the same may be applied 40 to hand threading shuttles or other types of shuttles.

In the drawings:

Figure 1 is a plan view of the front end of a shuttle adapted for use in an automatic filling replenishing loom.

Fig. 2 is a transverse sectional view on lines 2—2 Fig. 1.

Fig. 3 is a detail view, partly in longitudinal section, of the front end of the shuttle and threading device, showing the improved tension device applied thereto.

Fig. 4 is a detail view, partly in section, upon a plane extending transversely of the axis of the shuttle showing, however, the 55 tensioning device in elevation.

Fig. 5 is a side elevation of one form of threading device with the improved tension device applied thereto.

Fig. 6 is a side elevation of another form of threading device showing the invention 60 applied thereto, the anchoring means differing from that illustrated in Fig. 5, and,

Fig. 7 is a similar view of a threading device embodying the invention having another means for anchoring the tension device 65 therein.

The invention is disclosed in the accompanying drawing as applied to a usual form of shuttle for automatic filling replenishing looms comprising a body portion 1 having 70 a chamber 2 for a filling carrier 3 and a channel 4 leading from said chamber in the direction of the axis of the shuttle, the shuttle having a side eye 5 and threading slot 6 leading from said eye to the channel 4. 75

A threading device 7, which is secured within the channel 4, is provided with a thread passage leading to the eye and with means for directing the thread or filling running from the filling carrier into said 80 thread passage during the flight of the shuttle across the loom. The threading device may be constructed in any suitable manner to embody the improved tension device therein. In the preferred embodiment illustrated in the accompanying drawings the threading device 7 comprises a solid block having a thread passage 8 in the form of a cylindrical aperture or bore extending longitudinally therethrough and located substantially in the longitudinal axis of the shuttle. A second cylindrical aperture or bore 9 is located directly above the bore 8, said apertures or bores being located in such proximity that a portion of the wall between 90 them is cut away to form a threading slot 10. 95

The forward end of the threading device 7 presents an inturned beak 11 having a rearwardly extending horn 12 which projects across the vertical axial plane of the 100 shuttle and serves to prevent the filling from escaping from the thread aperture when introduced therein. The front wall of the beak 11 is so located as to form the rear wall of the threading slot 6 leading to the 105 eye 5 of the shuttle and desirably may be provided with a flanged portion 13 which enters a complementary notch in the body of the shuttle thus aiding in securing the threading device firmly in place. 110

The upper wall of the aperture or bore 9 is provided at one side of the vertical plane with a threading slot 14 extending longitudinally of the shuttle, the upper walls of the 5 threading device curving downwardly toward said slot to facilitate the introduction of the thread therethrough. The threading device is provided at its front end with a shield 15 which overhangs the beak 11 and 10 horn 12 and is supported therefrom a sufficient distance to permit the introduction of the thread, the beak and shield thus positioned providing means for guiding the thread into the threading slots 14 and 10 15 during the flight of the shuttle across the loom and serving to retain the thread within the thread passage 8 and eye 5 after it has been introduced.

The tension device comprises a bar 16 20 which extends longitudinally of the thread passage 8 and presents a helical rib, preferably of long pitch, which extends in the direction corresponding to that in which the thread is unwound from the filling carrier 25 so that the thread readily engages it when introduced into the thread passage. By reason of the fact that the bar 16 with the helical rib thereon extends substantially longitudinal of the axis of the thread passage, a 30 relatively long thread engaging surface is presented which will impose a sufficient tension upon the thread without bending the running thread to such an extent as to cause it to break.

The tension bar may be provided with a 35 helical spiral of such pitch as will produce the proper tension upon the running thread or filling, for it will be understood that the tension imposed upon the thread will be 40 proportional to the length of the pitch of said helical rib.

In the preferred embodiment of the invention herein the bar 16 is in the form of a 45 tapered flat plate which is twisted about its axis to present two helical ribs 17 and 18 which run in a direction corresponding to that in which the thread is unwound from the filling carrier, the flat or gently curved portion 19 between said ribs serving to engage the thread and impose tension upon it.

The tension bar 16, as illustrated herein, is provided at one end with an offset and 50 preferably wider portion 20 which is suitably anchored to the shuttle body or preferably to the end of the threading device which is nearer the chamber 2 of the shuttle body.

The free end 21 of the tension bar 4 desirably is located approximately opposite the 60 eye 5 of the shuttle so that the thread runs directly from the end of said threading device to the eye, desirably passing beneath a horn 22 extending downwardly from the beak 11 of the threading device.

65 Any suitable means may be provided for

anchoring the threading device in position. As illustrated in Fig. 3 the offset portion 20 of the tension bar extends into a recess 23 in the underside of the rear end of the thread guiding device 7 and is secured to said 70 thread guiding device by a screw or rivet 24.

In the embodiment of the invention illustrated in Fig. 5 the threading device 7 is provided with a rearward projection or boss 25 and the tension bar 16 is provided with 75 an offset extension which is folded around the end of the boss 25 and secured thereto by a screw 26.

The embodiment of the invention disclosed in Fig. 6 is similar to that illustrated 80 in Fig. 3, except that the under-face of the extension 27 of the tension device is flush with the under-surface of the threading device 7.

In the embodiment of the invention illustrated in Fig. 7 the threading device 7 is provided with a rearward extension 28 having a flange 29 extending upwardly in parallelism with the rear face 30 of the threading device 7 and the tension bar 16 is provided with an offset and folded anchoring portion 31 which lies between the flange 29 and the rear face 30 of the threading device.

A plate or shim 32 may be introduced between the anchoring portion 31 of the 95 threading device and the flange 29 and the upper end 33 of the flange 29 crimped over the shim in such a manner as to clamp it and the anchoring portion of the tension device firmly in position.

100 Various other expedients may be provided for securing the tension device in proper position in the thread passage of the threading device, or in the thread aperture in the shuttle if no threading device of the character disclosed is used.

105 It will be understood that various modifications in form, construction and arrangement of parts may be made within the spirit and scope of the following claims.

110 Having thus described my invention, what I claim as new and desire to secure by Letters Patent, is:

1. A loom shuttle having a chamber for a filling carrier, a thread delivery eye, a channel extending longitudinally of said shuttle leading to said eye, a threading device in said channel having a thread passage extending longitudinally of the shuttle and a tension device in said thread passage comprising a bar, extending in the direction of the axis of the shuttle, having a helical rib of long pitch.

115 2. A loom shuttle having a chamber for a filling carrier, a thread delivery eye, a channel extending longitudinally of said shuttle leading to said eye, a threading device in said channel having a thread passage extending longitudinally of the shuttle and a tension device in said thread passage com- 120 125 130

- prising a bar, extending in the direction of the axis of the shuttle, having a helical rib of long pitch, said helical rib running in a direction corresponding to that in which the 5 thread is unwound from the filling carrier.
3. A loom shuttle having a chamber for a filling carrier, a thread delivery eye, a channel extending longitudinally of said shuttle leading to said eye, a threading device in 10 said channel having a thread passage extending longitudinally of the shuttle and a tension device in said thread passage comprising a bar extending longitudinally of said thread passage, anchored at the end 15 nearest the shuttle chamber and having its other end free, said bar being provided with a helical rib of long pitch.
4. A loom shuttle having a chamber for a filling carrier, a thread delivery eye, a channel 20 extending longitudinally of said shuttle leading to said eye, a threading device in said channel having a thread passage extending longitudinally of the shuttle and a tension device in said thread passage comprising 25 a flat bar extending longitudinally of said thread passage and twisted to present helical ribs, and means for anchoring said bar at the end adjacent the chamber for the filling carrier.
5. A loom shuttle having a chamber for a filling carrier, a thread delivery eye, a channel 30 extending longitudinally of said shuttle, a transverse threading slot leading from said channel to said eye, a threading device in 35 said channel comprising a member having a beak, a shield overlying said beak, a thread passage extending longitudinally through said device and a tension device in said thread passage comprising a bar extending 40 axially of said thread passage and having a helical rib of long pitch.
6. A loom shuttle having a chamber for a filling carrier, a thread delivery eye, a chan-

nel extending longitudinally of said shuttle, a transverse threading slot leading from said channel to said eye, a threading device in 45 said channel comprising a block having a longitudinally extending cylindrical bore forming a thread passage, a longitudinally extending bore above said thread passage, the wall between said bores being slotted to 50 provide a guide-way for introducing the thread into said thread passage, a beak, a shield overlying said beak, and a tension device in said thread passage comprising a 55 bar extending in the direction of the axis of said thread passage and having a helical rib of long pitch.

7. A loom shuttle having a chamber for a filling carrier, a thread delivery eye, a channel 60 extending longitudinally of said shuttle leading to said eye, a threading device in said channel comprising a block having a longitudinally extending thread passage, a 65 tension device comprising a flat plate engaging the end of said block and having a tongue forming a bar extending longitudinally of said thread passage and twisted to present helical ribs of long pitch and means for anchoring said plate to said block. 70

8. A tension device for loom shuttles comprising a bar provided with a longitudinally extending helical rib of long pitch and provided with offset means at one end for anchoring the same in the shuttle to position said bar axially of the thread passage 75 leading to the shuttle eye.

9. A tension device for loom shuttles comprising a flat tapered bar twisted to form helical ribs and having means for anchoring 80 the same at the larger end in the shuttle to position said bar axially of the thread passage leading to the shuttle eye.

In testimony whereof, I have signed my name to this specification.

ARNOLD WILD.
